UNITED STATES PATENT OFFICE.

OMER LESTLY DOWNING AND HARLEY HENESY DULEY, OF CINCINNATI, OHIO.

ADJUSTABLE HANGER.

No. 909,769.

Specification of Letters Patent.

Patented Jan. 12, 1909.

Application filed April 28, 1908. Serial No. 429,678.

To all whom it may concern:

Be it known that we, OMER L. DOWNING and HARLEY H. DULEY, citizens of the United States of America, residing at Cincinnati, in the county of Hamilton and State of Ohio, have invented new and useful Improvements in Adjustable Hangers, of which the following is a specification.

This invention relates to adjustable hangers for concrete work, and one of the principal objects of the same is to provide means whereby a rod may be connected to a ceiling or floor and adjusted to the required position.

Another object of the invention is to provide a box or housing to be anchored into a concrete floor and to provide means whereby the head of a rod or bolt may be connected to the housing and adjusted to the required position.

These and other objects may be attained by means of the construction illustrated in the accompanying drawing, in which,—

Figure 1 is a sectional view taken through the housing embedded within the concrete floor and the head of a rod suspended from said housing. Fig. 2 is a sectional view on the line 2—2 of Fig. 1, showing the headed rod removed. Fig. 3 is a side elevation of the housing or casing. Fig. 4 is a central sectional view of the adjustable boss. Fig. 5 is a similar view of a slightly modified form of said boss.

Referring to the drawing for a more specific description of our invention, the numeral 1 designates a concrete floor, and embedded within this floor is a casing 2, said casing having upwardly extending T-shaped anchors 3. The housing is provided with inwardly extending base flanges 4, said flanges having notches 5 and intermediate points 6. On opposite sides of the casing perforated lugs 7 are provided.

The tapering boss 8 is provided with V-shaped lugs 9 which fit within the notches 5, the top or head of said boss having a central recess 10 for the head of the bolt and a central longitudinal bore 11. The head

portion of the loss extends beyond the V-shaped lugs 9, as at 12, to bear upon the flanges 4.

As shown in Fig. 5, the boss is provided with screw threads 13, and in this case the rod to be supported is provided with suitable screw threads to engage the threads 13. The rod 14 may have a head 15 thereon, and said head may fit in the recess 10 in the boss 8.

From the foregoing it will be obvious that our invention is of simple construction, can be readily embedded within a flooring or other concrete structure and can be adjusted by slightly raising the boss and moving it along the casing, as will be understood.

Having thus described the invention, what is claimed as new, is:

1. An adjustable hanger for concrete work comprising a casing provided with inwardly extending base flanges forming a longitudinal opening between them, a boss having flanges to bear on said base flanges, said flanges of the casing and of the boss having coacting means to lock the boss to the casing at any desired adjustment of the boss longitudinally of the casing, and a rod connected to the boss.

2. An adjustable hanger for concrete work comprising a casing having two upwardly extending anchors, said casing having inwardly extending notched flanges, a boss provided with V-shaped lugs to fit said notches and a central bore and a suspending rod extending through said bore.

3. In an adjustable hanger, a casing embedded within concrete material, inwardly extending flanges having notched edges, and a boss having a head provided with a recess, V-shaped lugs to fit said notches, and a rod suspended from said boss.

In testimony whereof we affix our signatures in presence of two witnesses.

OMER LESTLY DOWNING.
HARLEY HENESY DULEY.
